UNITED STATES PATENT OFFICE.

BENJAMIN G. KRAMER, OF ANDERSON, INDIANA, ASSIGNOR TO KRAMER VACUUM BRAKE COMPANY, OF ANDERSON, INDIANA, A CORPORATION.

VALVE CONSTRUCTION.

1,213,111.

Specification of Letters Patent. Patented Jan. 16, 1917.

Application filed January 24, 1916. Serial No. 73,907.

To all whom it may concern:

Be it known that I, BENJAMIN G. KRAMER, a citizen of the United States, and a resident of Anderson, county of Madison, and 5 State of Indiana, have invented a certain new and useful Valve Construction; and I do hereby declare that the following is a full, clear, and exact description thereof, reference being had to the accompanying 10 drawings, in which like letters refer to like parts.

The object of this invention is to provide a valve construction adapted to be used on internal combustion engines for utilizing the 15 vacuum produced by the action of the pistons therein. The power exerted by this vacuum can be readily utilized by this mechanism for operating different mechanisms of an automobile or the like, such as an air 20 brake, instead of being entirely wasted and unused.

The valve construction invented for utilizing this vacuum is comparatively simple in construction and yet completely controls 25 the use of vacuum and air pressure.

One feature of the invention consists in the construction of a cylinder and piston adapted to be operated from the foot board of an automobile so as to open and close 30 ports leading from the intake manifold and atmosphere.

Another feature of the invention is means operated by this piston for automatically closing a butterfly valve in said manifold 35 when it is desired to use the vacuum therein, thereby cutting off the supply of gas and throttling down the motor when the vacuum is used for operating an air brake or a similar device.

40 Still another feature of the invention consists in utilizing the oil saturated atmosphere of the crank case for keeping the air cylinder or the like properly lubricated.

The full nature of the invention will be 45 understood from the accompanying drawings and the following description and claims:

In the drawings, Figure 1 is a side elevation of the front portion of an automobile 50 showing the motor with a valve construction attached thereto. Fig. 2 is an enlarged view of a cross section through the line 2—2 of Fig. 1, showing the valve in position to utilize the vacuum. Fig. 3 is a section 55 through the line 3—3 of Fig. 2. Fig. 4 is a

cross section on the line 4—4 of Fig. 2. Fig. 5 is the same as Fig. 4, showing the valve in position to shut off the vacuum and open the intake valve. Fig. 6 is a cross section on the line 6—6 of Fig. 5.

In the drawings there is an automobile frame 10 having a radiator 11, dash 12 and foot board 13. There is shown therein an internal combustion engine 14 having a crank case 15 and a fly wheel 16. An intake manifold 17 connects the cylinders of said engine to the carburetor 18. Secured between the carburetor and said intake manifold there is a valve housing 19 having a flange 20 adapted to be secured between the intake pipe 21 and said carburetor by means of bolts fastened through the holes 22 therein. This admits of an open passageway 23 from the carburetor to the cylinders which is opened or closed by a butterfly 24 valve.

In one end of the casing there is a cylinder 25 having a reciprocating piston 26 therein, one end of said piston being connected to a foot pedal lever 27 by a connecting rod 28, said foot pedal having a spring attachment 29 for returning said piston to its normal position after being operated. In said cylinder there is a port 30 extending diametrically therethrough so as 35 to connect with a port 31 which leads to the passageway 23 above the butterfly valve so that when said butterfly valve is closed, said port 31 connects directly with the intake manifold 17. Extending diametrically 40 through said piston there is a passageway 32 adapted to register with the port 30 when the piston is pushed forward to its operative position, as shown in Fig. 2, thereby opening a complete passageway from the 45 intake manifold through the piston and cylinder to a pipe line 33 which leads to the piston 34 in the cylinder 134 to be actuated by the vacuum. This cylinder is of ordinary construction and may be for any appropriate use desired.

Extending radially from the cylinder and at right angles to the port 30, there is a port 35, as shown in Fig. 3, so that the ports 30 and 35 communicate with each 50 other and the port 31 is cut off when the piston is returned to its normal position, as shown in Fig. 5. This is accomplished by means of a passageway 36 near the head of said piston whereby the atmospheric pres- 55

sure may enter through the pipe line 37 and pass through the port 35, the passageway 36, the port 30 and the pipe line 33 into the cylinder head 134 whereby the piston 34 is returned to its normal position by a spring or any other suitable means when the atmospheric pressure is neutralized by being exerted on both sides thereof. The pipe line 37 is adapted to extend into the 10 crank case so as to take up the oil saturated air whereby the cylinders and pistons will be properly lubricated, at the same time being exposed to the atmospheric pressure.

Secured at one end of the piston 26 there 15 is a connecting rod 40 on a pin 41, said connecting rod extending through a head 42 and connected to the rod 28 by means of which said piston is actuated. Rigidly secured to the head of the piston by means 20 of screws 43 there is a frame 44 having a projection 45 adapted to engage and operate a lug 46. Secured to said lug and passing through the frame 19 and flange member 20, there is a shaft 47 which is secured to the butterfly valve 24 so as to operate it in the passageway 23, whereby said passageway will be opened and closed. There is a spring 48 on said shaft for returning the butterfly valve to its closed position when the lug 46 is released by the movement of the frame 44. Therefore, a slight movement of the piston from the position shown in Fig. 5 to that shown in Fig. 4 will release the lug and the butterfly 35 valve will be closed. On the other end of said shaft there is a set screw adjustment 49 for adjusting the butterfly valve to prevent its being entirely closed, if so desired.

The cylinder 25 is provided with a screw 40 50 having a projection 51 adapted to extend into a slot or groove in the piston 26 for preventing its turning therein.

The operation of the valve construction is as follows: When it is desired to operate the 55 piston 34 for putting on the brakes or any other purpose, the piston 26 is pushed inwardly by means of the rod 28, whereby the port 35 is closed and the butterfly valve 24 is closed by means of the spring 48, the lug 60 46 having been released by a very slight movement of the piston, a direct passageway then being opened from the intake pipe 21 to the intake manifold 17 through the port 31 directly through the piston, port 30 65 and pipe line 33 to the cylinder 134. A vacuum is thereby produced in the head of the cylinder 134 and the atmospheric pressure being exerted against the piston 34, forces it inwardly, thereby operating the 70 desired mechanism and at the same time the engine is throttled down, because of the closing of the butterfly valve, thereby cutting off the passage of the gas into the cylinders. When it is desired to release the 75 mechanism, the pedal 27 is released and the

spring 29 pulls the piston 26 back into normal position so that the passageway 36 registers with the port 35, thereby allowing atmospheric pressure to be exerted from the pipe line 37 through the cylinder and ports 70 and pipe line 33 to the piston 34 which neutralizes the atmospheric pressure on the other side thereof and permits a small spring or other similar means to return said piston to its normal position. Simulta- 75 neously with this movement, the butterfly valve will be opened by means of the projection 45 engaging the lug 46, thereby permitting the motor to speed up.

The above described valve construction is 80 adapted to be used with a cylinder such as the cylinder 134, shown in Fig. 1, to operate an air brake for automobiles. But it should be understood that it is not desired to limit this invention to that use, as it may 85 be adapted for various other purposes wherein it is desired to use the vacuum produced by the action of the motor.

The invention claimed is:

1. In combination with an internal combustion engine having an intake manifold, and a carburetor thereon, of a cylinder, a valve adapted to alternately connect said cylinder with said manifold and the atmosphere so as to operate the piston therein, 95 and means on said valve for automatically increasing and decreasing the quantity of gas entering said manifold so that said engine will be throttled down when the valve is opened to the manifold. 100

2. In combination with an internal combustion engine having an intake manifold, of a valve construction including a housing having a cylinder therein, a butterfly valve in said manifold, a port extending through 105 said cylinder to said manifold, a piston in said cylinder adapted to open and close said ports, a second port in said cylinder, means for operating said piston, and direct means on said piston for automatically opening 110 and closing said butterfly valve when said piston is operated.

3. In combination with an internal combustion engine having an intake manifold, of a valve construction including a housing having a cylinder therein, a butterfly valve in said manifold, a port extending through said cylinder to said manifold, a piston in said cylinder adapted to open said 115 ports, a second port in said cylinder, means for operating said piston, and a lug extending from said butterfly valve adapted to be engaged by said piston for closing said valve when said manifold port is opened. 120

4. In combination with an internal combustion engine having an intake manifold, of a valve construction including a housing having a cylinder therein, a butterfly valve in said manifold, a port extending through 125 said cylinder to said manifold, a piston in 130

said cylinder adapted to open and close said ports, a second port in said cylinder, means for operating said piston, a lug extending from said butterfly valve, and a projecting member on said piston adapted to engage said lug for closing said valve when said manifold port is opened.

5. The combination with an internal combustion engine having an intake manifold, of a valve construction including a housing having a cylinder therein, a port extending through said cylinder and opening into said manifold, a piston in said cylinder, a second

port in said cylinder open to the atmosphere, and means for operating said piston 15 so that it will slide in said cylinder whereby one of said ports will be brought into communication with the manifold.

In witness whereof, I have hereunto affixed my signature in the presence of the 20 witnesses herein named.

BENJAMIN G. KRAMER.
